SHIPPING DOCK BOARD

Gustaf Rydner, Detroit, Mich., assignor to General Motors Corporation, Detroit, Mich., a corporation of Delaware

Application August 25, 1941, Serial No. 408,199

8 Claims. (Cl. 14—72)

This invention relates to dock boards of the type used to span the floor gap between spaced floor structures. The ordinary plank to enable freight to be trucked between the freight car and the dock platform is laid across the intervening space with opposite edges resting on the two floor structures. Unless such edges bear directly on the floor surfaces they obstruct and interfere with smooth wheeling of the truck and constitute stumbling hazards and are likely themselves to become damaged and short-lived. If metal plates are used the edges tend to curl and ruffle, but in any event, one or the other plank edge is bound to be higher than the floor surface whenever the two floor structures are of unequal height or if the freight car sways on its supporting springs under the load of the truck passing over the plank on entering or leaving the car.

It is among the objects of the present invention to provide an improved dock board which compensates for rocking of the railroad car and which will promote safety by eliminating the likelihood of upwardly projecting edges under which a workman's foot might be crushed.

A further object is to provide a dock board which is especially adapted for use with spaced floor structures located at or deflected to different levels and which can be quickly and safely positioned and then held against creeping and displacement and which regardless of differences in or the cant of floor levels, obviates the before-mentioned difficulties with raised edges and insures a substantially continuous unbroken trucking surface from floor to floor.

Other objects and advantages will become apparent during the course of the following specification having reference to the accompanying drawing wherein Figure 1 is a sectional view showing the dock board in use; Figure 2 is a plan view of the dock board and Figure 3 is a detail section taken on line 3—3 of Figure 1.

In general the drawing illustrates a bridging ramp between different level floor structures with one edge resting on the lower level floor structure and with upstanding guide walls along both sides, each of which projects beyond the opposite edge of the ramp plate where it is fulcrumed in a bearing rocker shoe which rests on the surface of the upper level floor structure to suspend the ramp plate with its adjacent edge beside the edge of the higher floor structure and the top surfaces of the plate and floor structure substantially in line. The pivoted rocker shoe automatically compensates for variations in relative heights of floor structures with which the

5 dock board is used and also accommodates tilting of the car floor under changing load, thereby assuring a substantially continuous even surface for rolling trucks freely between the loading dock and freight car.

The high and low level spaced apart floor structures or platforms are indicated at 1 and 2 and either can be considered as being a freight dock, a warehouse or the like and the other as being, for example, a motor carrier or a freight car spotted on a railroad siding. The dock board bridging the intervening space consists essentially of a metal plate 3 having spaced structural stiffening ribs 4—4 welded on its underside. Upstanding side walls defining the width of the passageway afforded by the dock board and comprising metal rails 5—5 are welded on the upper face and along opposite ends of the plate 3. Each side wall 5 has an extension 5a projecting beyond 10 the edge of the plate 3 adjacent the high level floor structure 1 and the lower edge of the projecting extension 5a is straddled by a U-sectioned bearing foot 6 secured thereto by a fulcrum pin 7. To accommodate adjustment of 15 the bearing shoe 6 on its rock pin 7 the lower edge of the supporting bracket arm extension 5a is notched or cut away as at 8 and provides necessary clearance for a fairly wide range of relative movement called for by platform height 20 variations in different installations. The bearing shoe 6 on the overhanging extension 5a rests flat against the upper surface of the high level floor structure 1 and suspends the inclined ramp plate over the opening between the floor structures 1 and 2 with its edge substantially flush 25 with the floor surface.

If the spaced floor structures should be of 30 equal height either may be engaged by the rocker shoes, but otherwise the rocker shoes should be rested on the higher floor with the opposite edge resting on the lower floor. By 35 having the dock board suspended at one edge only it can bridge any size space as long as its opposite edge overhangs its supporting floor.

40 To strengthen the joint between the side wall 5 and floor plate 3 in the region where the greatest load will be transmitted therebetween a supplemental tie connection 9 may be used in the form of a U-shaped clip having its end flanges 45 fitted to the top edge of the wall 5 and underside of the plate and welded to both.

A rail 10 is welded on the underside of the plate 3 adjacent the suspended edge to provide 50 an abutment co-operable with the floor structure 1 for locating purposes and to prevent displace-

ment of the plate. Similarly a locating abutment may be provided along the opposite edge of the dock plate for engagement with the lower floor structure 2 so as to hold the dock board against creeping. This last mentioned locator preferably is in the form of one or more headed pins 11 insertable selectively through any of a series of spaced openings 12 extending through the dock board and a co-operating plate 13 welded on the upper face near the end of the board. The provision of a number of spaced locating openings 12 enables positioning of the locating pins 11 in accordance with the distance across the floor gap. To prevent accidental misplacement and loss of the pins, each is secured as by welding or the like to one end of a flexible chain 14 whose opposite end is secured near the top edge of an adjacent side wall 5.

Near each end the plate 3 is provided with openings, only one of which is shown as at 15, each opening being bridged by a pin 16 welded or otherwise secured on the underside of the plate. Also welded on the underside of the plate at the opening illustrated is one end of a flexible chain 17 of appropriate length whose free end terminates in a hook 18. Normally the hook 18 is suspended on the pin 16 adjacent the anchored end of the chain with the intermediate part of the chain hanging below the loading dock. This enables the hook to be picked up in the hand easily to pull the chain up through the opening. The purpose of the chain is to facilitate transferring the dock board from one place to another and when it is to be so carried the chain hook 18 is then engaged with the pin 16 of the other plate opening, spaced from the anchored end of the chain, so that the intermediate portion of the chain between its fixed end and hooked end is then located above the plate and affords a grab loop which can be picked up by the elevator of a conventional industrial lift truck for suspending the dock plate during its transfer.

I claim:

1. A dock board adapted to occupy the space between two floor structures and provide a connecting runway, comprising a bridging skid plate arranged at one edge to end short of and flush with an adjacent floor structure, a floor engaging and load sustaining bearing block, an outrigger rigid with the plate to overhang said floor structure and a fulcrumed weight transmitting connection supporting the outrigger directly in the bearing block.

2. A dock board for use between a loading dock floor and a carrier floor including a load sustaining bearer chair adapted to rest on one of said floors, a plate supporting bracket having a projecting end portion supported from the floor by said chair, a weight transmitting fulcrum connection between the bracket and the chair and a skid plate mounted on the bracket beyond the chair so that its edge will lie parallel to and beside the edge of said floor with its top surface substantially flush with the floor surface.

3. A removable ramp board for use with the edge of a floor structure to form a temporary flush extension of the floor including a ramp plate terminating in an edge adapted to lie beside and to end short of and in non-overlapping relation to the edge of the floor structure, plate supporting extensions at both sides of the plate projecting beyond said edge to overlie the floor

structure in spaced relation with the top thereof, floor engaging load sustaining pads beneath said extensions and axle pins connecting the extensions and pads and constituting fulcrum supports for the ramp plate.

4. A removable ramp board for use with the edge of a floor structure to form a temporary flush extension of the floor including a ramp plate terminating in an edge adapted to lie beside and to end short of and in non-overlapping relation to the edge of the floor structure, upstanding barrier walls at the opposite sides of the plate, each having an end portion extending beyond said plate edge and a pivoted plate suspension chair carried by each end portion to rest on the floor structure and to support said end portion clear of the floor.

5. A dock board to bridge the space between two floor structures located at different levels, including a floor plate having one edge resting on the lower level floor structure and its opposite edge suspended beside and ended short of the edge of the upper level floor structure, plate supporting outriggers projecting beyond the last mentioned plate edge in overlying spaced relation above the floor surface and having axle pins journaled therein, load sustaining chairs mounted on said axle pins to engage the upper level floor and locating abutments depending from the underside of the floor plate along both of its opposite edges for contact with said floor structures to resist horizontal plate displacement.

6. The structure of claim 5 where at least one of said locating abutments is adjustably mounted on the plate to fit the space presented between the floor structures.

7. In a dock board for use between spaced floor structures of different height, a bridging plate one of whose edge portions is adapted to overlap and rest on the lower floor structure with the other edge portion ending short of and adjacent the edge of the other floor structure, a supporting outrigger secured to the bridging plate and projected beyond the last mentioned edge portion for overhanging relation with the upper floor structure, a load sustaining rocker chair having a fulcrum bearing connection with the floor overhanging portion of the outrigger and being arranged to rest on the upper floor structure, and an adjustable locating abutment depending from the underside of the plate to engage the edge of the lower floor structure, said plate having a series of spaced openings for selective reception of said abutment as determined by the space between the floor structures and said abutment serving to prevent displacement of the load sustaining rocker chair from the upper floor structure.

8. In a dock board of the character described, a space bridging plate having a cable passage therethrough, a hook engaging formation on the plate in spaced relation to said opening, a flexible cable having one end secured below the plate at said opening and normally suspended beneath the plate, and a hook at the free end of the cable engageable with a retainer accessible through said passage, said hook and cable being arranged to be withdrawn upwardly through the passage and to be connected with said hook engaging formation in affording a grab loop.

GUSTAF RYDNER.
